[57] CLAIM

The ornamental design for a corner loudspeaker enclosure, as shown and described.

DESCRIPTION

FIG. 1 is a front perspective view of a corner loudspeaker enclosure showing my new design;
FIG. 2 is a front elevation of one of the speaker enclosures, separately shown for clarity of illustration;
FIG. 3 is a top plan view thereof;
FIG. 4 is a rear elevation thereof;
FIG. 5 is a top plan view of the header, shown separately for clarity of illustration;
FIG. 6 is a front elevation thereof;
FIG. 7 is a rear elevation thereof;
FIG. 8 is a front elevation of the base, shown separately for clarity of illustration, the undisclosed rear has a V-shaped configuration similar to FIG. 7; and
FIG. 9 is a front view of a modified embodiment of the speaker enclosure shown in FIG. 1.
